UNITED STATES PATENT OFFICE.

JOSEPH W. JONES, OF NEW YORK, N. Y.

JACK FOR WIRELESS TELEPHONY OR THE LIKE.

Application filed August 11, 1922. Serial No. 581,135.

To all whom it may concern:

Be it known that I, JOSEPH W. JONES, citizen of the United States, residing in the city, county, and State of New York, have invented a new and useful Jack for Wireless Telephony or the like, of which the following is a specification.

This invention is designed primarily for service in wireless-telephone apparatus, but is also applicable in switchboards of ordinary telephony and, indeed, in any service involving ready establishment and dis-establishment of one or more electric circuits. In the telephone-jacks heretofore known, the jack comprises an angular metal plate upon whose rearward prolongation is mounted, with suitable insulation, a plurality of forwardly-extending parallel contact-springs arranged in close proximity and parallel with the rearwardly-extending telephone-plug (when inserted). The close proximity of these elongated parallel contact-springs, however, results in capacity for induction of local circuits, particularly manifest in wireless telephony; the soldering of the circuit-wires to the rear ends of said contact-springs requires the service of skilled experts; and the jack-structure as a whole is unduly large and cumbersome.

The object of the present invention is to provide an improved telephone-jack that will be free from local induction, to which the circuit-wires can be readily connected by even an amateur, and which will occupy a far shallower space than the former jacks.

To this end, the invention comprises broadly a jack with its contact-spring or springs projecting rearwardly, in the same direction as the plug (when inserted). In such arrangement the contact-springs can be and preferably are far shorter, and spaced more widely apart, than heretofore; and thereby their capacity for local induction is eliminated, the circuit-wires can be readily connected thereto, and the whole structure is much shallower and does not usurp so much space in the wireless-apparatus (or telephone-switchboard) with which it is associated. The invention comprises further the various features of construction and arrangement hereinafter set forth and claimed.

The invention will be best understood by reference to the ensuing description and the accompanying drawings, which set forth several illustrative embodiments thereof. In said drawings:

Fig. I represents in transverse section one preferred embodiment of the invention, designed for employment with a single normally-open circuit, and shown as equipped with binding-posts for the circuit-wires;

Fig. II is a like view of a slight modification, which, instead of binding-posts, has simple terminals for soldering the circuit-wires;

Fig. III is a transverse section of another embodiment designed for a single normally-closed circuit;

Fig. IV is a similar view, and Fig. V a face-view, of still another embodiment for two circuits; and

Fig. VI indicates, in perspective, a plurality of jacks mounted upon a unitary or common base-plate and its unitary insulation-sheet.

Referring first to Fig. I, 7 represents a metal base-plate, shown as flat, and having a screw-threaded hole into which is to be screwed a tubular bushing 8, whereby said base-plate may be secured against the inner face of a wall or panel 9 (shown in dotted lines), ready for the insertion through said bushing of the usual or any desired form of telephone-plug. 10 is a sheet of insulation suitably secured to the rear face of said base-plate, as by a screw 11 (see Fig. V).

12 is one of the two complementary jack-terminals, here shown as a short binding-post, which is secured at the rear face of the insulation-sheet, as by a screw 13 inserted through the base-plate. 14 is the complementary jack-terminal or binding-post, secured directly to the rear face of said insulation-sheet, as by a screw 15 inserted through a clearance-hole 16 in the base-plate.

17 is a single rearwardly-projecting contact-spring, flat and preferably quite short, which is suitably secured in electric contact with said second jack-terminal 14, as by being clamped between the foot of said terminal 14 and the rear face of said insulation-sheet by said screw 15. Along its rearwardly-extending portion, at 18, said contact-spring is so shaped or distorted as to project laterally into position for electric contact with the usual contact-ball 19 carried at the end of the well-known telephone-plug having the usual contact-sleeve 20.

The device shown by Fig. II is quite similar to that of Fig. I. But the binding-posts are dispensed with, and a single substantially J-shaped flat spring-member,

- preferably quite short, is secured directly against the rear face of the insulation-sheet 10 as by a screw 15' inserted through a clearance hole 16' and held in place by a nut.
- 5 The longer arm 17' of said member projects rearwardly and is distorted to extend into the path of the plug; while the other end is provided with a hole 17" or the like for soldering one of the circuit-wires. The other 10 jack-terminal 12' consists merely of a short metal member held in electric contact with the base-plate, as by a screw 13', and may likewise be provided with a hole or the like for soldering its circuit-wire.
- 15 In Fig. III there are two rearwardly-projecting short, flat contact-springs, 21 and 22, secured by the two binding-posts 12 and 14 respectively, and having their rear ends normally in contact to constitute a 20 closed-circuit arrangement. When the telephone-plug is inserted, as indicated in Fig. III, its ball 19 forces said contacting-ends apart, and thereby introduces into the circuit of said springs the telephone (or other 25 instrument) whose terminals are carried by said plug.
- In Figs. IV and V there are four short, flat, rearwardly-projecting contact-springs, whose flat rear ends are brought into mutual 30 parallelism. As here shown, these four springs are mounted 90° apart around the central plug-hole, with spring 23 and the diametrically-opposite spring 24 secured respectively under the binding-posts. Spring 23 is in electric contact with the base-plate, while spring 24 and the other two springs, 25 and 26, are secured upon the insulation-sheet (as through clearance-holes, such as 16 in Fig. I). As shown, the rearwardly-extending flat main portions of the four springs occupy respectively planes which constitute substantially a rectangle. At the rear of each of the springs 25 and 26 is a lateral projection which is bent around inwardly, as 18', and then directly across, terminating (as "inner" ends) between the rear ends of springs 23 and 24 (as "outer" ends). Said inner ends are out of contact with each other, but each inner end is in 40 electric contact with the adjacent outer end. The inner portions of the two springs 23 and 24, which carry said outer ends, are distorted (as at 18, in Fig. I), to extend into contact with the plug-ball 19 when inserted; and along the inner face of said spring 23 is an insulation-strip, as 27, to insulate that spring from the plug. When the plug is inserted, its ball 19 forces apart the rear ends of springs 23 and 24, thereby 45 breaking the two contacts aforesaid, and introducing the plug and the telephone (or other instrument whose terminals are carried by said plug) into a new circuit which comprises said contact-springs 23 and 24.
- In Fig. VI, 28 represents the rear face of a sheet of insulation which lies flush in a rabbet or recess in the rear face of a unitary metal plate 29, which latter is provided with a plurality of holes 30 for the insertion (from the front) of a telephone-plug or 50 plugs. To said insulation is secured (as by screws through clearance-holes in the metal plate, as already described) a plurality of terminals 31, one for each hole; each of said terminals carries or constitutes a short rearwardly-projecting contact-spring (similar to member 17' in Fig. II); while, for each terminal 31, there is secured directly to the common metal base-plate a complementary terminal 32, here shown as like terminal 12' of Fig. II. However, binding-posts, such as shown in Fig. I, might be employed; and for one or more of the holes, there may be two or more contact-springs (as indicated by Figs. III-V).
- 55 Various embodiments of the invention have thus been described in great fullness of detail, but only for the sake of clearness, since the invention is not limited to any particular embodiment or to the particular 60 structures and arrangements herein set forth, but may be embodied in any desired form within the spirit of the appended claims.
- What is claimed is:
1. A telephone-jack, comprising a flat metal base-plate having a sheet of insulation secured to the rear face thereof, the two being provided with a hole for the insertion of the telephone-plug, four short and flat contact-springs located substantially ninety degrees apart at the rear face of said insulation, one of said springs being in electric connection with said base-plate, and the other three being secured through clearance-holes therein directly to said insulation, the flat rearwardly-projecting portions of said springs occupying respectively planes which constitute substantially a square, the rear ends of two of said springs 105 having lateral projections bent into parallelism with and extending as inner ends between the outer rear ends of the other two springs, a strip of insulation located on the inner face of one of the two last-mentioned 110 or outer members, said two inner ends being out of contact with each other and each of said two outer ends being in electric contact with the adjacent inner end, and said outer ends being separable further apart for 115 breaking the two contacts aforesaid by the insertion of the telephone-plug, whereby the instrument such as a telephone whose terminals are carried by said plug is introduced into a new circuit comprising the two outer ends aforesaid.
- 120 2. The herein-described telephone-jack, comprising a base-plate, an insulation-sheet, four rearwardly-projecting contact-springs, of which only one is mounted in electrical 125

In Fig. VI, 28 represents the rear face of

connection with said base-plate, while the other three are mounted on said insulation-sheet, the rear ends of said four springs being arranged in mutual parallelism, two of said rear ends projecting as inner ends between the other two as outer ends, each inner end being normally in electric contact with the adjacent outer end, and said two contacts being separable by the introduction 10 between said outer members of the telephone-plug, and thereby the instrument such as a telephone whose terminals are carried by said plug being simultaneously introduced into a new circuit comprising 15 said two outer ends.

3. The herein-described telephone-jack, comprising a base-plate, an insulation-sheet, four rearwardly-projecting contact-springs, of which only one is mounted in electrical 20 connection with said base-plate, while the other three are mounted on said insulation-sheet, the rear ends of said four springs being parallel, two of said rear ends projecting as inner ends between the other two as 25 outer ends, the two inner ends being out of contact with each other, but each inner end being normally in electric contact with the adjacent outer end.

4. A telephone-jack comprising a flat 30 and plane base-plate of metal having a screw-threaded hole, a flat and plane sheet of insulation secured on the rear face thereof and having a hole registering with the first-mentioned hole, a headed and externally-threaded hollow bushing engaging said screw-threaded hole in the base-plate 35 for clamping the latter upon a panel, a jack-terminal mounted in electric contact with said base-plate and projecting rearwardly beyond said insulation-sheet, a second jack-terminal connected through a clearance space in said base-plate to the rear face of said insulation-sheet, and a rearwardly-projecting contact-spring electrically connected at the rear face of said insulation-sheet to said second terminal.

5. A telephone-jack comprising a base-plate of metal having a screw-threaded hole, a sheet of insulation secured on the 50 rear face thereof and having a hole registering with the first-mentioned hole, a headed and externally-threaded hollow bushing engaging said screw-threaded hole in the base-plate for clamping the latter upon a panel, two complementary jack-terminals, one mounted in electric contact with said base-plate and the other mounted upon said insulation-sheet, and a rearwardly-projecting contact-spring electrically connected at the rear face of said insulation-sheet to said 55 second terminal.

6. A jack comprising a base-plate of metal having a screw-threaded hole, a sheet of insulation secured on the rear face thereof and having a hole registering with the

first-named hole, a headed and externally-threaded hollow bushing engaging said screw-threaded hole in the base-plate for clamping the latter upon a panel, two complementary jack-terminals, at least one of them mounted upon the rear face of said insulation-sheet, and a rearwardly-projecting contact-spring electrically connected at the rear face of said insulation-sheet to the last-mentioned terminal.

7. A jack comprising a base-plate of metal having a hole, a sheet of insulation secured on the rear face thereof and having a hole registering with the first-named hole, means comprising an externally-threaded 75 hollow bushing engaging said plate concentrically with said hole for clamping said base-plate upon a panel, two complementary jack-terminals, at least one of them mounted upon the rear face of said insulation-sheet, and a rearwardly-projecting contact-spring electrically connected at the rear face of said insulation-sheet to the last-mentioned terminal.

8. A demountable make-and-break attachment, comprising a metal plate having a hole therethrough, a sheet of insulation secured thereto and having a hole registering with the first-named hole, a hollow sleeve projecting from said holes and adapted to be inserted through a hole in a panel-board, means upon said sleeve for clamping the above-named parts to said panel-board, and two complementary jack-terminals carried respectively by said metal plate and 90 said sheet of insulation.

9. The herein-described jack-structure, comprising a unitary metal plate provided with a plurality of holes for the insertion of a telephone-plug, a sheet of insulation covering a portion of the surface of said plate, a jack-terminal and a rearwardly-projecting contact-spring secured at the rear surface of said insulation, one for each 100 of said holes, and a complementary jack-terminal secured in electric contact to the rear face of said metal plate.

10. A telephone-jack comprising a flat metal base-plate having a sheet of insulation secured to the rear face thereof, the two being provided with a hole for the insertion of the telephone-plug, four short and flat contact-springs located substantially ninety degrees apart at the rear face of said insulation, one of said springs being in electric connection with said base-plate, and the other three being secured directly to said insulation and out of electric contact with said base-plate, the flat rearwardly-projecting portions of said springs occupying 115 respectively planes which constitute substantially a square, the rear ends of two of said springs having lateral projections bent into parallelism with and extending as 120 inner ends between the outer rear ends of 125 said springs.

the other two springs, a strip of insulation located on the inner face of one of the two last-mentioned or outer members, said two inner ends being out of contact with each other and each of said two outer ends being in electric contact with the adjacent inner end, and said outer ends being separable further apart for breaking the two contacts aforesaid by the insertion of the telephone-
13 plug, whereby the instrument such as a telephone whose terminals are carried by said plug is introduced into a new circuit comprising the two outer ends aforesaid.

11. A telephone-jack comprising a flat and plane base-plate of metal having a screw-threaded hole, a flat and plane sheet

of insulation secured on the rear face thereof and having a hole registering with the first-mentioned hole, a headed and externally-threaded hollow bushing engaging said 20 screw-threaded hole in the base plate for clamping the latter upon a panel, a jack-terminal mounted in electric contact with said base-plate and projecting rearwardly beyond said insulation-sheet, a second jack-terminal connected directly to said insulation-sheet and out of electric contact with said base-plate, and a rearwardly-projecting contact-spring electrically connected at the rear face of said insulation-sheet to said 30 second terminal.

JOSEPH W. JONES.
